UNITED STATES PATENT OFFICE.

VERNOR T. BARKLEY, OF PITTSBURGH, PENNSYLVANIA.

CAR DUMP.

Application filed June 30, 1920. Serial No. 392,972.

To all whom it may concern:

Be it known that I, VERNOR T. BARKLEY, a citizen of the United States, and resident of Pittsburgh, in the county of Allegheny and State of Pennsylvania, have invented a new and useful Improvement in Car Dumps; and I do hereby declare the following to be a full, clear, and exact description thereof.

My invention relates to dumping apparatus, and it has special reference to apparatus for dumping coal cars in which the car is partially or entirely inverted to discharge its load.

The object of my invention is to provide a car dump of the above-indicated character which shall be simple in structure and which shall operate rapidly and positively to handle cars of ordinary construction. My car dump consists essentially of an oscillating frame carried upon a stationary shaft, and oscillated by means of a manually-controlled fluid-pressure cylinder, together with means for automatically receiving cars and locking them in position on the frame during the dumping operation, and for thereafter automatically releasing the empty car and permitting it to leave the dump by gravity or to be pushed from the dump by the next succeeding car.

The details of my invention may best be understood by reference to the accompanying drawing, in which Fig. 1 is a side elevational view of a car dump constructed in accordance with my invention; Fig. 2 is a plan view of the same apparatus with the car-retaining horns removed; Fig. 3 is a transverse view, partly in elevation and partly in section along the line 3—3, Fig. 2, the extreme dumping position of the car and supporting frame being shown in dotted lines; Fig. 4 is a transverse view, partly in elevation and partly in section, the section being taken substantially along the line 4—4, Fig. 2. Fig. 5 is a fragmentary cross-sectional view showing the manner in which the horn-releasing trigger is moved away from the track; Fig. 6 is a fragmentary view, similar to Fig. 5, showing the means for opening the horns; and Fig. 7 is a detail view of the cradle-holding latch.

As shown in the drawings, a stationary shaft 2 is mounted in suitable bearings 3 carried by fixed supports 4. A frame or cradle is loosely mounted for oscillation on the stationary shaft 2 and consists of side plates 5 and end plates 6, secured together

by means of angle bars 7. The frame also has intermediate transverse plates 8. All of the plates 6 and 8 carry bearings 9 for supporting the frame upon the stationary shaft 2. The frame may also be provided with top and bottom plates, in order to enclose the working parts and protect them from dust.

The frame just described carries a pair of parallel tracks 10 which, when the dump is in its load-receiving position as shown in the drawing, are in alignment with stationary tracks 11. In order to hold the dump stationary while the cars are being placed upon and removed from it, I provide a stoppin 12 surrounded by a spring 13 which is confined between a fixed bracket 14 and a collar 15, and which tends to force the pin 12 outward to enter a latch 16 disposed in a recess formed in one of the stationary supports.

The construction of the latch 16 is shown in Fig. 7. It consists of a cup-shaped member 17 within which are secured two short parallel pivot-pins 18, each of which carries a latch member 19 having an inclined upper end 20 and having a short lug 21 extending inwardly from its lower end. A spring 22 is disposed between the latch members 19 and is confined between an upper plate 23 and a lower plate 24 which rests upon the lugs 21. Near the end of its reverse oscillation the dump rotates to bring the pin 12 down upon the inclined faces 20 of the latch members 19. The latch members separate and allow the pin 12 to move down upon the plate 23 thus stopping the dump in the proper position, the shock being cushioned by the spring 22. At the same time, the pressure of the spring 22, increased by the downward thrust of the pin 12, immediately closes the latch members 19 and the pin is prevented by the overlapping ends of the latch members from moving upward. It may, however, be withdrawn lengthwise from the latch, and in order that this may be done when the dump is ready to make its next oscillation, the pin 12 is connected by means of a link 25 to a lever 26 which is secured to a rock shaft 27 that carries a trigger 28 extending into the path of one of the front wheels 29 of the car 30 as it runs upon the dump. When the trigger 28 is depressed by the wheel 29, the pin 12 is withdrawn from the latch in the locking seat 16 and this leaves the dump free to ro-

2
state. When the trigger 28 is withdrawn laterally from contact with the wheel 29, in the manner described below, the spring 13 returns the pin 12 to its locking position. 5 This takes place during the return movement of the dump, and just before the cradle reaches its upright position.

In order to automatically clamp the loaded cars 30 to the dump, I provide a pair of 10 horns 31 adapted to grip and hold the front wheels of the car, and a similar pair of horns 32 to grip and hold the rear wheels of the car. The front and rear horns at 15 each side of the car are secured to a shaft 33 that is mounted in bearings 34 attached to the tracks 10, and is surrounded by a spring 35 which is confined between a collar 36 and one of the bearings 34 and which provides for a small amount of lengthwise 20 movement of the cradle 33 to absorb the shock which takes place when the loaded cars strike the horns 31.

The trigger 28 is intended to be depressed by the front wheel 29 only and not by the 25 rear wheel of the car, in order that the pin 12 may not be withdrawn from the latch 16 by the rear wheel of the empty car as it leaves the dump. For this purpose, and for the purpose of releasing the pin 12 at 30 the proper time to stop and lock the dump, the rock shaft 27 which carries the trigger 28 is slidable lengthwise in bearings 37, as shown in Fig. 5, and is moved back and forth in response to the movement of one 35 of the forward horns 31. This horn is provided with a downward extension 38 which has an opening to receive the end of a curved finger 39 that is loosely mounted on the shaft 27 between collars 40. When the 40 forward horns 31 are in their gripping position, as shown in Fig. 3, the trigger 28 is in the path of the wheel 29; but when the horns swing outward to release the wheels, as shown in Fig. 5, the extension 38 acts 45 through the finger 39 to move the shaft 27 to the right, Fig. 5, carrying the trigger 28 away from the track 10. The rear wheel may then pass the trigger 28 without engaging it.

50 The horns 31 which grip the front wheels of the car are connected to move together pivotally around their shafts 33 and the horns 32 which clamp the rear wheels of the car are similarly connected to move together, as shown in Fig. 4. It is necessary 55 that the front horns 31 be in their operative gripping position when a loaded car comes upon the dump, and that the rear horns 32 be swung out at this time to permit the 60 loaded car to enter between them. When the front wheels of the car are in position against the horns 31, the rear horns must close upon the rear wheels and all the horns must remain in their gripping positions 65 while the dump is being rocked to dump the

car and to return the car to its starting position. Thereupon the horns must open to release the car and when the car has cleared the front horns, these horns must close again in order to stop the next succeeding car. 70

To carry out these movements of the horns, each pair of horns is connected by means of downward extensions 45 and links 46 to a triangular rocking lever 47 which is loosely mounted upon the stationary shaft 2 between a fixed collar 48 and a sleeve 49. A spring 50 is connected at one end to the lever 47 and at its other end to one of the cross bars 6 of the frame and tends to move the lever 47 into the position shown in full lines on Fig. 4, at which time the horns are in their gripping position. The lever 47 is provided with a lug or extension 51 adapted to engage a cam pin 52 which is slidably carried in bearings 53 formed on the fixed sleeve 49, and is surrounded by a spring 54 which normally tends to force the pin 52 into the path of the lug 51. The horn-operating construction just described is provided both for the front pair of horns and for the rear pair of horns. 80 85 90

In order to withdraw the cam pin 52 which controls the front pair of horns, this pin is connected by means of a hook joint 55 with a rod 56 surrounded by a spring 57 and connected by means of a link 58 to a lever 59 mounted on a rock-shaft 60 to which is also secured a trigger 61 that extends into the path of the wheels of the car near the point where the car leaves the dump. The hook joint 55 provides for rotation between the parts of the joint when the cradle rotates. A hand lever 72, pivoted to the cradle frame at 73, has a forked portion 74 that works between collars 75 on the shaft 60. By means of this hand lever, the shaft 60 may be moved lengthwise to remove the trigger 61 from the path of the car wheels when cars are to be run across the dump without dumping. 100 105 110

To withdraw the cam pin 52 which controls the rear horns 32, I provide the rear pin 52 with a head 65 which is engaged by a forked lever 66 pivotally mounted at 67 on a bracket 68 and connected by means of a link 69 to a lever 70 that is rigidly secured to the rock-shaft 27. Thus, when the trigger 28 is depressed and the shaft 27 is rocked to release the locking pin 12, the same movement of the shaft 27 withdraws the rear cam pin 52 and releases the rear horns 32, permitting them to close upon the rear wheels of the car under the pull of the spring 50. 115 120 125

The operation of the horns may best be understood by referring to Figs. 4 and 6. When the dump is oscillated to dump a car, each of the cam pins 52 is forced by its spring 54 into the path of movement of the 130

corresponding lug or extension 51 of the rocking lever 47 which is connected to one of the pairs of horns by the links 46. As the dump returns to its upright position, 5 the lugs 51 engage the pins 52, as shown in Fig. 6, and are thereby stopped, and on the further oscillation of the dump the levers 47 remain stationary, thus rocking the horns outward into the positions shown in 10 Fig. 6. This releases the empty car, which then runs from the dump. One of the front wheels of the car depresses the trigger 61, which pulls the forward cam pin 52 away from the lug 51, and permits the spring 50 15 to pull the forward horns 31 to their gripping position. When the next car reaches the forward horns 31, one of its front wheels depresses the trigger 28, which pulls the rear cam pin away from the rear lever 20 47, thus permitting the rear spring 50 to close the rear horns 32.

As will be seen in Fig. 4, each lug 51, when the horns are upright, rests against a fixed stop member 76, and the pivotal connections 77 and 78 between the lever 47 and the links 46 are respectively above and below the lines joining the center of the shaft 2 with the pivots 79. Therefore, the horns can only be opened by the positive rotation 30 of the lever 47 and cannot be opened by force applied accidentally or otherwise to the horns themselves, which would only press the lugs 51 more tightly against the stop members 76.

35 For oscillating the dump frame around the shaft 2, I provide a cylinder 80 operated by fluid pressure and provided with trunnions 81 which support the cylinder between the central plates 8 of the cradle frame. 40 The piston of the cylinder is connected by means of a connecting rod 82 and a crank pin 83 to a crank 84 which is rigidly secured to or integral with the shaft 2. Air, water or other operating fluid is supplied to the cylinder 80 through a pipe 85 controlled by 45 a suitable valve 86. The connection between the pipe 85 and the inlet port of the cylinder is made by means of a rubber hose connection 87, in order to permit the necessary rocking movement of the cylinder. The 50 cylinder may be either single-acting or double-acting, as desired.

The air cylinder 80 is provided with a one-way exhaust valve 95, Fig. 3, which may be 55 operated either manually or automatically just before the return movement of the dump. This valve is at the lowest part of the cylinder when the cradle is in the dumping position, and when the exhaust begins. 60 Therefore, any water which may be carried into the cylinder along with the air, will be thoroughly blown out at each stroke of the cylinder. This is a feature of special advantage over apparatus which has heretofore been operated by compressed air, and

in which the air cylinders have been liable to freeze in cold weather.

In order to prevent the coal from escaping from the car before the car reaches its dumping position, I provide a dump plate 70 88, shown in Fig. 3, which holds the load in the car until the car is in the dotted-line position, as shown in Fig. 3.

A counterweight 89 is secured to the under side of the cradle and is so proportioned 75 as to substantially balance the cradle when a loaded car is in position thereon. This permits the dump to be oscillated with a minimum expenditure of power, and also serves to return the dump to its starting position 80 when the load is dumped, the side of the tilted dump frame carrying the counterweight being then heavier than the side carrying the empty car.

The operation of my device is started with 85 the front horns 31 in their holding position, the rear horns 32 open, and the locking pin 12 in the latch 16. A loaded car rolls upon the dump in the direction of the arrow, Fig. 1, and is stopped by engagement of its front 90 wheels with the horns 31, the shock being taken up by the springs 35. At the same time, one of the front wheels of the car depresses the trigger 28, thus withdrawing the pin 12 from the latch 16 and also withdrawing 95 the rear cam pin 52 from the lug 51 on the rear rocking lever 47. The rear horns are thus released and the rear spring 50 causes them to close and grip the rear wheels. The operator then moves the valve 100 105 86 to admit fluid to the cylinder 80 causing the piston to be drawn into the cylinder, whereby the dump is tilted to the dotted-line position shown in Fig. 3 and the car is dumped. To return the dump and the car to their starting position, the operator moves his control valve to exhaust the cylinder and the counterweight 79 brings the dump to its upright position. The speed with which the dump rocks to dump the car and to return 110 the car to its starting position may be readily controlled by the operator who may, for example, admit a small amount of fluid in the cylinder in order to cushion the return movement.

115 As the dump is returned to its upright position, the locking pin 12 snaps into the latch 16 and the front and rear horns are simultaneously opened by engagement between the lugs 51 and the cam pins 52, in the manner described above. The empty car is therefore free to roll from the dump or to be pushed therefrom by the next succeeding car. One of the front wheels of the empty 120 car depresses the trigger 61 as it leaves the dump and this rocks the shaft 60 and withdraws the pin 40 from the forward lever 47, thus releasing the front horns 25 and causing them to rise to their holding position, ready to stop the next car coming upon 125 130

the dump. The above series of operations are repeated, and the only attendant required is the operator who controls the air valve.

It is to be understood that the structural details which I have herein shown and described may be varied in many respects without departing from my invention, and I therefore desire that no limitations be imposed upon my invention except such as are indicated in the appended claims.

What I claim is:

1. In a car dump, the combination of a stationary shaft, a car support mounted on the said shaft and rotatably movable thereon, means for securing a car on the said support, means operated by the cars moving upon the said support for operating the said securing means, and means operatively connected to said stationary shaft for moving the said support to dumping position, and for returning the said support to loading position.

2. In a car dump, the combination of a stationary shaft, a car support mounted on the said shaft and rotatably movable thereon, means for securing a car on the said support, means operated by the cars moving upon the said support for operating the said securing means, a fluid-operated cylinder carried by said support, and connections between the said cylinder and the said shaft for moving the said support to dumping position and for returning the said support to loading position.

3. In a car dump, the combination of a stationary shaft, a car support mounted on the said shaft and rotatably movable thereon, means for securing a car on the said support, means operated by the cars moving upon the said support for operating the said securing means, a fluid-operated cylinder carried by the said support, and connections from the said cylinder to move the said support to dumping position and to return the said support to loading position.

4. In a car dump, the combination of a stationary shaft, a car support mounted on the said shaft and rotatably movable thereon, a crank carried by the said shaft, and a cylinder carried by the said support, and having its piston connected to the said crank.

5. In a car dump, the combination of a stationary shaft, a car support mounted on the said shaft and rotatably movable thereon, a stationary crank carried by the said shaft, a cylinder carried by the said support and having its piston connected to the said crank, and means for supplying fluid under pressure to the said cylinder.

6. In a car dump, the combination of a stationary shaft, an oscillable car support mounted on said shaft, a crank carried by said shaft, and a fluid-operated cylinder carried by the said support, the said cylinder having its piston connected to said

crank and being provided with an exhaust valve disposed at the lower end thereof when the said cradle is tilted to its dumping position.

7. In a car dump, the combination of a stationary shaft, a car support mounted on the said shaft and rotatably movable thereon, means for securing a car on the said support, means operated by the cars moving on the said support for operating the said securing means, a fluid-operated cylinder carried by said support, and connections between said cylinder and said shaft for operating the said support.

8. In a car dump, the combination of a stationary shaft, a car support mounted on the said shaft and rotatably movable thereon, means for securing a car on the said support, means operated by the cars moving on the said support for operating the said securing means, a fluid-operated cylinder carried by the said support, and connections between the said cylinder and the said shaft for operating the said support.

9. In a car dump, the combination of a stationary shaft, a car support loosely mounted on the said shaft and movable from car-receiving position to dumping position, means for locking the said support in car-receiving position, and means operable by the cars moving on the said support for automatically releasing the said locking means.

10. Car dumping apparatus comprising a shaft, a rotatably movable car support mounted on the said shaft, and means for regulating the speed of rotation of the said support, the said regulating means comprising a cylinder carried by the said support and movable therewith, the said cylinder being operatively connected to the said shaft.

11. Car dumping apparatus comprising a rotatably movable support and horns for securing a car to the said support, the said horns being adapted to operate to grip the individual wheels of the car by movement of the car on the support, and for release of the gripping action by rotary movement of the support.

12. Car dumping apparatus comprising a shaft, a rotatably movable car support mounted on the said shaft, means for securing a car to the said support, the said securing means comprising horns adapted to grip the individual wheels of the car, and means operable in response to the rotation of the said support, for releasing the said horns from the said wheels.

13. Car dumping apparatus comprising a shaft, a rotatably movable car support mounted on the said shaft, front and rear horns carried by the said support and adapted to grip and hold the individual front and rear wheels of a car, means car-

- ried by the support for releasing all of the said horns from the said wheels to enable the car to leave the dump, means carried by the support for thereafter bringing the front horns to their holding position, to receive another car, and means carried by the support for bringing the rear horns to their holding position after the said car has engaged the front horns.
- 10 14. Car dumping apparatus comprising a shaft, a rotatably movable car support mounted on the said shaft, front and rear horns carried by the said support and adapted to grip and hold the individual front and rear wheels of a car, means operable in response to the rotation of the said support for releasing the said horns from the said wheels, means operable by a car leaving the dump for bringing the front horns to their holding position, and means operable by a car running upon the dump for bringing the rear horns to their holding position.
- 15 15. In a car dump, the combination of a stationary shaft, a car support mounted loosely on the said shaft and rotatably movable thereon, and means for operatively connecting the said shaft to the said support for controlling the movement of the said support.
- 20 16. In a car dump, the combination of a stationary shaft, a car support mounted on the said shaft and rotatably movable thereon, automatically operable means carried by the support for clamping a car on the said support and means operated by the car moving upon the said support for operating the said clamping means.
- 25 17. In a car dump, the combination of a stationary shaft, a car support mounted on the said shaft and rotatably movable thereon, a pair of horns adapted to engage and hold the front wheels of a car, a second pair of horns adapted to engage and hold the rear wheels of the said car, a trigger operatively connected to the said front pair of horns and operable by the car leaving the said support to move the said front horns to wheel-engaging position, and a second trigger disposed near the said front pair of horns and operatively connected to the said rear horns, the said second trigger being operable by the car as it approaches the said front horns to move the said rear horns into wheel-engaging position.
- 30 18. In a car dump, the combination of a stationary shaft, a car-support mounted on the said shaft and rotatably movable thereon, a pair of horns pivotally secured to the said support and adapted to engage and hold two of the wheels of a car, a member loosely mounted on the said shaft, links connecting the said horns to the said member, whereby the said member rotates with the said support, means for stopping the rotation of the said member to cause the said horns to release the said wheels, and means operable by the said car for causing the said member to return the said horns to wheel-engaging position.
- 35 19. Car dumping apparatus comprising a shaft, a rotatably movable car support mounted on the said shaft, means for securing a car to the said support, the said securing means comprising horns adapted to grip the individual wheels of the car, means operable in response to the rotation of the said support for releasing the said horns from the said wheels, and means operable by the movement of a car moving on said support for causing the said horns to move into their operative position.
- 40 20. Car dumping apparatus comprising a shaft, a rotatably movable car support mounted on the said shaft, means for securing a car to the said support, the said securing means comprising horns adapted to grip the individual wheels of the car, and means for moving the said horns to and from their operative position, the horn moving means being wholly actuated by mechanism contained within the said support.
- 45 21. Car dumping apparatus comprising a rotatably movable car support, means for causing the said support to stop in car receiving position, means operable by the movement of a car on said support for releasing said support, and means for thereafter controlling the movement of said support, all of the said operating and controlling parts being located within the frame of the said support.
- 50 22. Car dumping apparatus comprising a rotatably movable car support, means for holding a car upon said support, means for releasing the said holding means from the said car, a trigger disposed in the path of movement of the car leaving said support for restoring said holding means in position to stop the next car, and a manually operable lever for moving the said trigger out of its operative position, whereby the said car holding mechanism may be rendered inoperative to permit cars to move across the said support without being stopped thereon.
- 55 23. In a car dump, the combination of a stationary shaft, a car support loosely mounted on the said shaft and rotatably movable thereon, means for engaging and holding a car on the said support, and means for alternately moving the said car holding means into and out of their operative position, the said moving means being connected to the said stationary shaft and being operated thereby.
- 60 24. Car dumping apparatus comprising a rotatably movable car support and means for locking the said support in car-receiving position, the said locking means comprising a stop member carried by the said support, means for engaging the said stop member to

- stop the rotation of the said support, and means for withdrawing the said stop member from the said engaging means, thereby permitting the said support to again rotate.
25. Car dumping apparatus comprising a rotatably movable car support and means for locking the said support in car-receiving position, the said locking means comprising a stop member carried by the said support, means for engaging the said stop member to stop the rotation of the said support, and means automatically operable by a car moving on the said support for withdrawing the said stop member from the said engaging means, thereby permitting the said support to again rotate.
26. Car dumping apparatus comprising a rotatably movable car support, a stationary member adjacent to said support, a latch carried by the said stationary member, a stop member carried by the said car support and adapted to engage the said latch to stop the rotation of the said support, and means automatically operable by a car moving on the said support for withdrawing the said stop member from the said latch.
27. Car dumping apparatus comprising a rotatably movable car support, a stationary
- member adjacent to said support, a latch carried by said member and comprising two pivotally movable spring-pressed hooks, a stop member carried by the said car support and adapted to separate the said hooks and thereafter to be retained between them, and means automatically operable by a car moving on the said support for withdrawing the said stop member lengthwise from the said latch.
28. Car dumping apparatus comprising a rotatably movable support, a stop pin carried at one end of the said support and spring-pressed outwardly, a trigger in the path of movement of a car moving on the said support and operatively connected to the said stop pin, and a latch disposed adjacent to the said car support and adapted to engage and hold the said stop pin, the said pin being withdrawn from the said latch when the car moves on the said support and depresses the said trigger.
- In testimony whereof, I the said VERNOR T. BARKLEY, have hereunto set my hand.
- VERNOR T. BARKLEY.
